PRESSING IRON HAVING STARCH
DISPENSING MEANSFrank Giarrappa, 3013 Brighton 6th St., and Jack L. Most,
3129 Coney Island Ave., both of Brooklyn, N.Y.
11235Filed Oct. 23, 1965, Ser. No. 503,628
5 Claims. (Cl. 38—78)

This invention relates generally to pressing irons, and is especially concerned with a unique and highly improved construction for spraying starch in conjunction with a pressing iron.

As is well known to those versed in the art, the spraying of starch during the ironing procedure is most inconvenient, presently requiring placement of the iron in its holder, raising of the starch container and dispensing therefrom of the starch. While prior proposals have been made for attaching a starch container to an iron, these proposed devices have been roughly complex in construction, unreliable in operation, and have not found acceptance by the purchasing public.

Accordingly, it is an important object of the present invention to provide a highly improved pressing-iron construction wherein a container of liquid starch under pressure may be neatly and conveniently incorporated in the handle of the iron, completely concealed therein, and whereby the starch contents may be quickly and easily sprayed or dispensed, when and where desired, by the user of the iron without movement of the user's hand, and during the actual ironing procedure.

It is a further object of the present invention to provide a pressing iron of the type described wherein starch may be quickly and easily applied to the garments being ironed, in a most expeditious manner, which substantially completely eliminates the time and effort previously required in applying liquid starch.

It is a further object of the present invention to provide a pressing iron having the advantageous characteristics mentioned in the preceding paragraphs, which is extremely durable in construction, reliable in operation throughout a long useful life, neat and attractive in appearance, and which can be economically manufactured for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a top perspective view showing a pressing iron constructed in accordance with the teachings of the present invention, and illustrating a container of pressurized liquid starch adapted for insertion in the pressing iron; and

FIGURE 2 is a partial longitudinal sectional view taken generally along the line 2—2 of FIGURE 1, illustrating the starch container in operative association with the pressing iron.

Referring now more particularly to the drawings, and specifically to FIGURE 1 thereof, a pressing iron is there generally designated 10, and the liquid-starch container is generally designated 11.

The pressing iron includes an elongate body or base 12, which may be generally conventional, of a forwardly and rearwardly elongate configuration and having a generally flat bottom for pressing engagement with a garment.

2

Upstanding from the upper side of the body 12, at forwardly and rearwardly spaced locations therealong, are a rearward support 13, and a forward support 14. The forward and rearward supports 14 and 13 may be of hollow, plastic or other suitable insulating material, and have their lower ends firmly anchored to the body 12, by any suitable means.

Extending longitudinally of the body 12, in spaced relation thereover, is a generally hollow, tubular handgrip 15 having its forward end 16 fixed to the front upstanding support 14, and its rearward end 17 fixed to the upstanding rear support 13. In practice, the handgrip 15, and upstanding supports 13 and 14 may be integrally formed, as by molding, say of suitable plastic material.

15 The elongate handgrip 15 may be of a generally tubular, interiorly hollow construction, say having a rear open end, as at 18 in FIGURE 2. The rear-end opening 18 may continue forward in a generally cylindrical interior formation, as at 19, being closed to the rear support 13, as by a wall 20. The forward support 14 may open to the front interior region of the hollow 19, and a vertically elongate opening or slot 21 may be formed in the upper front region of forward support 14 in a general alignment with the cylindrical hollow 19.

20 25 Interiorly of the handgrip 15, in the forward region of hollow 19, adjacent to but spaced rearwardly from the front handgrip end 16, there is provided an internal shoulder 23, which may depend from the upper wall of the handgrip. A bracket or seat 24 projects forwardly from the lower end of the shoulder 23 toward but terminating short of the front handgrip end wall 16. Spaced over the seat 24, the upper wall of the handgrip 19 is cut away, as at 25, defining a thru opening generally over the forward support 14. The opening 25 extends rearwardly to form 30 an upwardly facing recess 26 in the top wall of the handgrip 15 extending rearwardly beyond the depending internal shoulder or abutment 23.

35 Received in the top wall opening 25 of the handgrip 15 is a lever, generally designated 28, which may be of generally angulate configuration, including a forward depending arm 29, and an arm 30 extending generally rearward from the upper end of arm 29. The forward arm 29 depends into the forward region of the handgrip 15 between the shoulder 23 and forward end wall 16 of the handgrip, 40 while the arm 30 extends rearwardly over and beyond the shoulder 23, being received in the recess 26 and there pivotally mounted, as by a laterally extending pin 31 passing through the arm 30 and into the handgrip 15 on opposite sides of the recess 26.

45 50 Thus, the lever 28 is swingable about the axis of pin 31. A resilient element or spring 32 may be interposed in compressed relation between the underside of arm 30 and the upper side of seat 24 to urge the lever 28 in its clockwise direction of swinging movement, as seen in FIGURE 2. The depending arm 29 may be provided with an offset portion or upwardly facing shoulder 33 engageable with the interior top wall of handgrip 15 to limit clockwise swinging movement of the lever. By

55 60 manual actuation, as by depression in the direction of arrow 34, the lever 28 may be swung from its solid-line position of FIGURE 2, to the dot-and-dash outline position shown therein.

The container 11 may include a generally cylindrical body 36 adapted for frictional engagement in the handgrip hollow 19 through the rear end opening 18. At one end of the cylindrical container body 36 may be provided a dispensing nozzle 37 of the conventional type adapted to dispense upon angular deflection out of alignment with the body 36, say to the phantom position shown in FIGURE 2. The container 11 itself may thus be conventional, and is sized for insertion into the handgrip hollow 19 to a stop or limiting position in engagement with the

shoulder 23, with the container body 36 just received in the opening 18. In this condition, the nozzle 37 has its distal end projecting through the slot at 21, normally at an upper region of the slot. The nozzle 37, when the container 11 is inserted in the handgrip 15, extends across the path of movement of the lower end of depending lever arm 29, so that movement of the lever 28 effects downward deflection of the nozzle 37 to the phantom position shown in FIGURE 2. That is, the nozzle 37 moves along the slot 21. In the deflected phantom position of nozzle 37, liquid starch is sprayed, as at 39, exteriorly of the pressing iron for application to a garment being pressed. Of course, this operation may be conveniently actuated by a user's finger or thumb depressing the lever 28; and, upon release of the lever the nozzle 37 returns to its undeflected closed condition in the upper region of slot 21. Obviously, this spray application may be quickly, easily and conveniently applied, even during the pressing operation or motion of the user, to effect substantial savings in time and effort.

Although the present invention has been described in some detail by way of illustration and example for purposes of clarity of understanding, it is understood that certain changes and modifications may be made within the spirit of the invention and scope of the appended claims.

What is claimed is:

1. A pressing iron comprising a body having its underside adapted for pressing engagement with a garment, support means upstanding from said body, an elongate handgrip spaced over said body and carried by said support means, said handgrip being interiorly hollow and having an opening at one end, a container of pressurized starch in said hollow of said handgrip, a dispensing nozzle on said container extending spacedly through the opening of said handgrip and deflectable to spray starch exteriorly of said handgrip, and hand-actuable operating means mounted on said handgrip for movement into and out of deflecting engagement with said nozzle.

2. A pressing iron according to claim 1, said container being removably engaged through the other end of said handgrip.

3. A pressing iron according to claim 1, said operating means comprising a lever pivotally mounted on said handgrip having one end interiorly of said handgrip for engagement with the nozzle and extending exteriorly of said handgrip for manual engagement by an operator.

4. A pressing iron comprising an elongate body having its undersurface adapted for pressing engagement with a garment, support means upstanding from said body at longitudinally spaced locations therealong, an elongate tubular handgrip extending longitudinally of and spaced over said body and carried by said support means, said handgrip having one end open and having a slot at its other end, a shoulder in said handgrip adjacent to and spaced from said other end thereof, a container of pressurized starch removably inserted in said handgrip through said open end into abutting engagement with said shoulder, a dispensing nozzle on said container extending spacedly through said slot and deflectable to emit starch exteriorly of said handgrip, and hand-actuable operating means on said handgrip for movement into and out of deflecting engagement with said nozzle.

5. A pressing iron according to claim 4, said operating means comprising a lever pivotally mounted on said handgrip extending interiorly thereof for engagement with said nozzle and exteriorly of said handgrip for manual engagement by an operator, and resilient means in said handgrip engaging said lever to urge the latter toward its position of movement out of deflecting engagement with said nozzle.
